UNITED STATES PATENT OFFICE.

WILLIAM JOHN TONKIN, OF RIDGEWOOD, NEW JERSEY.

DESIGN FOR A GAME BOARD.

Application filed October 22, 1925. Serial No. 15,224. Term of patent 7 years.

To all whom it may concern:

Be it known that I, WILLIAM JOHN TONKIN, a citizen of the United States, residing at 167 Woodside Ave., Ridgewood, in the county of Bergen and State of New Jersey, have invented a new, original, and ornamental Design for Game Boards, of which the following is a specification, reference being had to the accompanying drawing, forming part thereof.

I claim:

The ornamental design for a game board, as shown.

WILLIAM JOHN TONKIN.
